CLAIM

I claim the ornamental design for a pneumatic fastener, as shown.

DESCRIPTION

FIG. 1 is a front elevation view showing my new design;
FIG. 2 is a top plan view thereof;
FIG. 3 is a left side elevation view thereof;
FIG. 4 is rear elevation view thereof;
FIG. 5 is a right side elevation view thereof; and,
FIG. 6 is a bottom plan view thereof.

1 Claim, 2 Drawing Sheets

FIG. 2

FIG. 3

FIG. 1

FIG. 5

FIG. 6

FIG. 4
